DESIGN FOR AN ELASTIC FABRIC

Fredric Ruhroth, New Bedford, Mass., assignor to Continental Elastic Corporation, New Bedford, Mass., a corporation of Delaware

Application April 10, 1940, Serial No. 91,584

Term of patent 7 years

To all whom it may concern:

Be it known that I, Fredric Ruhroth, a citizen of Germany, residing at New Bedford, in the county of Bristol and State of Massachusetts, have invented a new, original, and ornamental Design for an Elastic Fabric, of which the following is a specification, reference being had to the accompanying drawing, constituting a part thereof.

Fig. 1 is a plan view of the fabric showing my
new design;

Fig. 2 is an edge view thereof; and
Fig. 3 is a rear view thereof.

The design comprises a tubular elastic fabric
having the rear face thereof flat and the front face thereof Shirred.

I claim:

The ornamental design for an elastic fabric,
substantially as shown and described.

FREDRIC RUHROTH.
